TAP MOUNTING AND CLOSURE MEANS FOR
BARRELS AND LIKE CONTAINERS

Albert Louis Maggenti, San Francisco, Calif.

Application September 27, 1937, Serial No. 165,789

3 Claims. (Cl. 217—98)

My present invention relates to a tap or faucet mounting and closure means for barrels and like containers, and more particularly to a combined closure and mounting means which will facilitate the mounting of a tap or faucet upon a barrel, cask or other like container with a screw threaded connection.

An object of my invention is to provide a simple and novel means for mounting a threaded tap or faucet upon a barrel, cask or like container.

Another object of my invention is to provide a threaded tap supporting means for a barrel or cask, having means associated therewith, by which the barrel or cask may be closed and sealed for transit when the threaded tap or faucet is not mounted therein.

Another object of my invention is to provide a new and novel tap mounting means for a barrel or the like, having a closure means which may be sealed in its closed position to protect the contents of the barrel when the latter is in transit.

Another object of my invention is to provide a closure means for a tap mounting of the character described, in which the closure means is held in a non-interfering position when a tap is threaded into the tap mounting.

Other objects and advantages of my invention will be in part evident to those skilled in the art, and in part pointed out hereinafter in connection with the accompanying drawing wherein there is shown, by way of illustration and not of limitation, a preferred embodiment thereof.

In the drawing:

Figure 1 is a fragmentary perspective view showing my improved tap mounting and closure means as it appears when mounted upon the end of a barrel or cask.

Figure 2 is a fragmentary sectional view showing the details of the tap mounting and closure means illustrated in Figure 1, and

Figure 3 is a perspective view of the tap mounting with its associated closure means in an open position.

For the purpose of illustrating my invention I have shown an embodiment thereof which is particularly adapted for application to a wooden barrel or cask, such as is commonly used for the transportation of wines and liquors.

As shown in Figure 1 of the drawing, the tap mounting means is positioned upon the head of a barrel 10 closely adjacent its staves 11. When applied to a barrel as shown, the tap mounting is covered by a concealing plate 12 having hinge forming ears 13 at the upper edge thereof, and hinged upon the ears 13 there is a cover or clo-

sure member 14 which cooperates, as will herein-after appear, with the tap mounting means to seal the barrel when in transit. At the lower end of the plate 12 there is an outwardly extending protuberance 15 that is adapted to project through an opening 16 at the free end of the closure member 14, and extending transversely through a hole in the protuberance 15 there is a pin 17, by means of which the closure member 14 may be secured in its closed position 10 upon the plate 12. The pin 17 may be of any suitable character. For example, it may be a straight pin or, if desired, it may be in the form of a wedge that will tightly hold the closure member in its barrel closing position. To prevent tampering with the contents of the barrel, I may also provide an aperture in the end of the pin 17 through which the wires of a lead seal 18 may be extended. When such a seal 18 is provided, the contents of the barrel will be protected 20 against dilution and/or tampering when in transit.

Reference is now made to Figure 2 of the drawing for a more detailed description of the invention. As shown in this figure of the drawing, 25 the tap mounting means comprises an internally threaded bushing 19 which extends through an opening 20 in the barrel head 10, and as shown, it carries an outer bushing of rubber 21 that insures a tight fit between the barrel head and the bushing 19 at this point. The outer end of the bushing 19 has an enlarged irregular or hexagonal head portion 22 in which there is formed a recess seat 23 for a rubber or cork gasket 24. The hexagonal head 22 of the bushing 19 may be recessed into the head 10 of the barrel so as to prevent a turning thereof, as when a tap is screwed therein, or it may be extended outwardly beyond the surface of the barrel head 10 and recessed into the plate 12, as shown at 25. In this 30 latter event, when the plate 12 is secured upon the barrel head 10, as by wood screws 26, the bushing 19 will be firmly held in the head 10 of the barrel. With this arrangement it will be seen that when the closure member 14 is in 45 its open position, a tap or faucet (not shown) may be readily screwed into the internally threaded bushing 19 to withdraw the contents of the barrel therethrough.

For the purpose of effectively sealing the barrel, as when in transit, the closure member 14 is provided with an inwardly extending portion 27 that extends through a central opening in the plate 12 and engages the gasket 24, previously referred to as mounted at the outer end of the 55

tap mounting bushing 19. When the closure member 14 is thus positioned upon the plate 12 and secured in place by means of the pin 17, as described in connection with Figure 1 of the drawing, the contents of the barrel will be prevented from escaping through the tap mounting. As an additional sealing means to prevent the accidental loss of liquid, I may also provide a rubber gasket at each side of the plate 12. One such rubber gasket, designated by the numeral 28, is shown as disposed between the plate 12 and the barrel head 10, and another similar gasket 29 is shown as disposed between the outer surface of the plate 12 and the hinged closure member 14.

For the purpose of holding the closure member 14 in a position where it will be out of interfering relation with a tap when mounted upon the barrel, I provide a spring 30 at the hinged connection between the plate 12 and the closure member 14. This spring 30 is arranged to exert an opening bias upon the closure member 14 and it is of sufficient strength to firmly hold the closure member 14 in an elevated position, as illustrated in Figure 3 of the drawing, when it is not secured in its barrel closing position upon the plate 12, as previously described.

While it is permissible to use a metal tap or faucet with certain liquors, such as are transported in barrels, there is a disposition to avoid the use of metal, and particularly corrosive metals in connection with wine barrels, and therefore, in order to provide a tap mounting which will be free of this objection, I form my tap mounting bushing 19 of porcelain or glass, and if desired, I may also place a non-corrosive facing 31 upon the inner end of the projection 27 of the closure member 14. When such a facing 31 is provided, it will be seen that the contents of the barrel will be held out of contact with all metal parts of the closure and mounting member. As an alternative form, it is also contemplated that I may construct the bushing 19 and the other parts of my improved mounting means of a non-corrosive metal.

Upon referring back to Figure 3 of the drawing, it will be noted that the plate 12 and the hinged closure member 14 are made relatively thin, and as a result, these members will be protected by the projecting ends of the staves 11 when the barrel is placed on its end.

While I have, for the sake of clearness and in order to disclose my invention so that the same can be readily understood, described and illustrated a specific device and arrangement, I desire to have it understood that this invention is not limited to the specific means disclosed, but may be embodied in other ways that will suggest themselves to persons skilled in the art. It is be-

lieved that this invention is new and it is desired to claim it so that all such changes as come within the scope of the appended claims are to be considered as part of this invention.

Having thus described my invention, what I claim and desire to secure by Letters Patent is—

1. In a tap mounting for a barrel or the like, the combination of an internally threaded non-metallic bushing adapted to be inserted in the wall of a wooden container, said bushing having an irregular shape at its outer end, a plate disposed over the end of said bushing and secured upon the wall of the container, said plate having a central opening through which a tap may be threaded into said bushing and a recess of irregular shape for the end of said bushing, whereby said bushing will be held against turning when a tap is threaded therein, and a hinged closure member mounted upon said plate having a central portion adapted to engage and close the open end of said bushing when the tap mounting is not in use.

2. In a tap mounting for a barrel or the like, the combination of an independent internally threaded non-corrosive bushing adapted to be inserted through the wall of a barrel and receive a screw-threaded tap, said bushing having an enlarged head of irregular shape at its outer end interlocking with the wall of the barrel to prevent a turning thereof when the tap is screwed therein, a plate for holding said bushing against displacement from the wall of said barrel having a central opening through which the tap may extend when screwed upon said bushing, and a hinged closure member mounted upon said plate having a non-corrosive portion adapted to engage and close the threaded opening of said bushing when the tap is removed therefrom.

3. In a tap mounting for a barrel or like container, the combination of a container, an internally threaded bushing disposed in and extending through a wall of said container, said bushing having a shoulder at its outer end of irregular shape recessed in the wall of said container to prevent a turning thereof, a retaining plate for said bushing secured to the wall of said container independently of said bushing and having a central opening through which a tap carried by said bushing may extend, a closure member hingedly mounted upon said retaining plate and having a portion extending through the central opening in said retaining plate and engaging said bushing to close the threaded opening thereof when the tap is removed therefrom, and means carried by said plate for securing said closure member in its closed position to thus seal the opening through said bushing.

ALBERT LOUIS MAGGENTI.
